UNITED STATES PATENT OFFICE.

WILLIAM H. HUFFMAN, OF BEAVER FALLS, PENNSYLVANIA.

RAIL-BRACE.

No. 899,302.

Specification of Letters Patent. Patented Sept. 22, 1908.

Application filed May 22, 1907. Serial No. 375,146.

To all whom it may concern:

Be it known that I, WILLIAM H. HUFFMAN, a citizen of the United States of America, residing at Beaver Falls, in the county of Beaver and State of Pennsylvania, have invented certain new and useful Improvements in Rail-Braces, of which the following is a specification, reference being had therein to the accompanying drawing.

10 This invention relates to rail braces, for connecting the rails of a railway track, and its primary object is to provide simple and inexpensive means for firmly connecting together and bracing the two rails of a track to prevent spreading of the rails.

A further object of the invention is to provide a connecting brace for railway rails which in addition to its function as a brace, will serve as a securing device for the splice-bars or fish-plates of the rails thus avoiding the employment of bolts for that purpose, and the weakening of the rails by the formation in their web portions of a number of bolt holes.

25 The construction of the improvement will be fully described hereinafter, in connection with the accompanying drawing which forms a part of this specification, and its features of novelty will be set forth in the appended 30 claims.

In the drawing:—Figure 1 is a transverse section of a railway track with my improvement applied thereto, and, Fig. 2 is a similar view illustrating a modification of the invention.

35 Referring to Fig. 1, the reference numerals 1 and 2 designate the track rails supported upon ties 3. The rails are connected together by a metal bar consisting of two counterpart sections 4 and 5, each provided at its outer end with a threaded rod extension 6, extending through an opening in the rail, and also through the splice bars 7 arranged on opposite sides of the rail at joints. The 45 splice-bars are formed with openings registering with the opening in the rail, and upon the projecting outer end of the rod extension 6 is a nut 8 bearing against the outer splice-bar, and serving to firmly hold the 50 outer end of the brace section. The inner ends of the brace sections are reduced to provide round rod extensions 9, which are connected by a turn-buckle 10 as shown.

The utility and operation of the improved brace will be obvious, and it provides a substantial connection between the rails firmly bracing them transversely, and at the same time securing the splice-bars upon the rails. The brace sections may be readily tensioned by means of the turn buckle.

55 In the modification shown in Fig. 2, the brace consists of a continuous rod 11 formed with threaded rod extensions 13 at its opposite outer ends. The said threaded end extensions of the rod 11 extend through registering openings in the rails and splice bars. Nuts 12 and 15 are fitted upon the threaded ends 13 to rest against the outer splice-bars and the end portions 14 of said rod 11 bear against the inner splice-bars as shown, to 60 firmly hold the said rod and bind the splice-bars to the rails. This modified embodiment of the invention avoids the use of the turn-buckle, but in both forms of the invention shown is disclosed the important feature 65 of securing the splice-bars upon the rails without employing supplemental bolts and nuts.

70 Having fully described my invention what I claim and desire to secure by Letters Patent, is:—

75 In a rail brace, the combination with the rails, and the fish plates engaging the rails at their meeting ends, of a rail brace comprising two counterpart members, each member comprising a flat body portion having reduced cylindrical threaded ends, the said reduced threaded ends of both members being in the same plane, the outer end of each member projecting through the fish plates 80 and the webs of the rails, nuts thereon to secure the said members in the fish plates and rails, said members and the nuts serving to bind the fish plates in position against the rails, and a turn-buckle connecting the adjacent inner ends of said members, said turn-buckle lying in the same plane as the members.

85 In testimony whereof I affix my signature in the presence of two witnesses.

WILLIAM H. HUFFMAN.
